ATT'YS.

UNITED STATES PATENT OFFICE

HARRY G. KNOX, OF NEW YORK, N. Y., ASSIGNOR TO R. HOE & CO., INC., OF NEW YORK,
N. Y., A CORPORATION OF NEW YORK

PRINTING MACHINE

Application filed June 29, 1926. Serial No. 119,268.

This invention relates to certain improvements in multiple unit printing machines.

In certain types of printing machines such as, for instance, high speed rotary machines, the press comprises a large number of printing units, each unit comprising printing and perfecting couples, and suitable folder units. The units are arranged in line or in lines, each line comprising the desired number of printing units, folder or other units. To insure accurate printing, the units must be accurately aligned, that is, the axes of the printing cylinders should be either parallel or in line with each other. These units are erected on a support or foundation, and frequently it takes considerable time and trouble to obtain the correct initial alignment of the various independent units. Furthermore, even if the initial alignment is correct, the units may have to be subsequently re-aligned due to settlement of the foundation or other causes, and re-alignment for these reasons is particularly troublesome. Furthermore, on account of the size of the machine, the present methods of determining alignment, to wit, levels and wires, are difficult and take up an undesirable amount of time.

It is the especial object of the present invention to provide, in a press construction involving a number of units, a construction by which the press may be readily and quickly set up in correct alignment and, if any re-alignment is necessary, this can be easily and quickly accomplished.

It is a further object of the invention to provide an improved arrangement for determining the accuracy of the alignment of the units and a means by which this can be easily and quickly accomplished.

It is a further object of the invention to provide an improved unit, either a press unit or a folder, or other unit which can be pre-erected or partially pre-erected and standardized so that the units may be transported as a whole and set up in assembled form in such arrangements as the user may desire.

With these and other objects not specifically referred to in view, the invention consists in certain novel parts, arrangements and combinations which will be described in con-

nection with the accompanying drawings and the novel features pointed out in the claims hereunto annexed.

In these drawings,—

Figure 1 is a side elevation of a multi-unit machine and a folder, showing a construction and arrangement embodying the invention; 55

Figure 2 is a sectional plan view, the section being taken on line 2—2 of Fig. 1, showing the means for aligning the press, the view 60 being taken in the direction of the arrow;

Figure 3 is a detail side view, on an enlarged scale, looking in the direction of the arrow 3 of Fig. 2;

Figure 4 is an enlarged sectional view taken 65 on the line 4—4 of Fig. 2, looking in the direction of the arrow 4 of that figure;

Figure 5 is a detail view of one means that may be employed for checking up the alignment of a number of units; 70

Figure 6 is a side elevation of a modified arrangement having a frame structure with printing units mounted in a plurality of tiers; and 75

Figure 7 is a side elevation of another modification having the printing units arranged with their cylinders in line.

Referring to these drawings, the particular machine selected to illustrate the invention is a multi-unit press having similar units arranged in line with a folder at the end. It will be understood, of course, that the invention is not to be restricted to such a number of units, but any number or arrangement of units desired may be employed and units which are 80 not duplicates of each other. 85

In the preferred construction and arrangement of the press, however, each printing unit will be similarly constructed so that all the units will be duplicates of each other, and similarly the folding or other units will be duplicates of each other, and the units may be pre-erected each complete in itself, whether printing or folding unit, so that these units can be transported as a whole and set up in any 90 arrangement desired and aligned, as herein-after referred to. The printing units being identical in the arrangement shown, a description of one will suffice for all. 95

In the particular construction shown, there 100

are three press units, A, B, C, and a folder F, and a description of unit A will suffice for the printing units. As shown, each unit comprises upper and lower horizontal side frames 1, 2, these frames being connected by vertical standards 3, 4, and 5, on each side of the machine. The side frames 1, 2 are connected by cross frames 7. The unit is supported on a base 8 to which it is secured in any suitable way, as by bolts 9. Supported in these frames is a press comprising printing and perfecting couples, the cylinders of which may be, as shown, arranged in parallel relation. The form cylinders of the couples are marked 10, 11, and the impression cylinders 12, 13. The form cylinders are inked from any suitable inking mechanism, indicated generally by the numerals 14, 15, these parts being suitably supported in the side frames before referred to. The units and their bases are supported on a suitable foundation, indicated as a bed 16, supported on suitable standards 17 rising from any suitable support. It will be understood, of course, that instead of this bed the couples may be supported on the floor of the press room or on any other suitable foundation. The units are or may be tied together by top frames 10' which are secured in standards 11' so that they may have a limited movement for a purpose hereafter referred to, as by a slot arrangement, indicated at 12'.

These couples are driven in any usual or desired manner, but preferably so that any unit may be thrown out of action when desired. In the particular construction shown, each unit is driven by a vertical shaft 18, the upper end of which is provided with a miter 19 which gears with a miter 20 on one of the impression cylinders of the unit. This shaft, in the particular construction shown, drives the impression cylinder 13, this cylinder, through suitable gearing, driving the other couple of the press. The driving shafts 18, on their lower ends, are provided with miters 21 which mesh with miters 22 on a power shaft 23 extending the length of the machine. These miters 22 are arranged so that they can be slipped out of mesh with the miters 21 so that any unit may, if desired, be cut out.

The units may be pre-erected complete or substantially complete, transported in erected or partially erected form, and set up on the foundation. In accordance with the invention, means are provided for aligning these units when they are set up or afterwards so that the cylinders will be parallel or so that the units may be adjusted as desired or necessary, which means will be of such character that the aligning, either initially or subsequently, may be readily and quickly effected. While this means may vary within wide limits, in the particular construction shown, the unit is so arranged that it can be

raised or lowered, and can also be swung or turned around the drive shaft 18 as a center, so that the units may be aligned as desired or necessary. As shown, referring first to the devices for raising or lowering the units, there is provided at each corner of the unit an adjusting device shown in the form of a wedge. While the specific construction of these adjusting wedges may be varied, in the particular construction shown, at each corner of the unit, the foundation has secured thereto a wedge plate 25 having an inclined surface 26, these wedge plates being secured in position in any suitable manner, as by screws 27. Co-operating with the wedge plate 25 is a wedge block 28 having a wedge surface 29 cooperating with the inclined surface 26 of the wedge plate 25. The wedges are beneath the units, which rest on these wedges at each corner, and by manipulating these wedges a unit may be raised or lowered to effect parallelism of the cylinders with the cylinders of other units. To manipulate the wedges, each wedge block 28 is provided with a threaded stem 30 on which are set up nuts 31, 32, the nut 31 bearing against the outside of a leg 33 projecting upwardly from the wedge plate 25. By adjusting these thrust nuts, the wedges may be moved back and forth to raise or lower the unit, as desired, the arrangement of the top frames permitting this movement. Stop screws 39 are or may be provided at each side of the stem 30 for holding the wedge block in adjusted position.

In constructions embodying the invention, means are provided for giving the units a swinging or turning movement so that the units can be accurately aligned horizontally and, in the particular construction shown, the units for this swinging movement are swung around the driving shaft 18 as a center. Various constructions may be employed for effecting this movement. As shown, the foundation or base 16 has suitably secured thereon, at each corner of the unit, a bracket 34 having an upstanding leg 35 through which passes a stop screw 36 provided with a lock nut 37. Also secured to the base, at each corner, is a bracket 41' through which passes an adjusting screw 40, this adjusting screw being provided with a lock nut 41. In adjusting the unit, the unit may be raised or lowered vertically by the manipulation of the wedges 28. The unit may be swung horizontally around the shaft 18 as a center by loosening the stop screws 36 at the corners and the lock nuts 41, whereupon, by manipulating the proper adjusting screw 40 which bears against the base 8' of the unit, the unit may be given a swinging movement. When the unit is properly adjusted, the other adjusting screws 40 are tightened up, as are also the stop screws 36, so that the unit is held in its adjusted position.

In the best construction, an improved

means will be provided for checking up the aligning of the units. While these means may vary somewhat in construction, in the preferred form suitable devices will be provided, connected with each unit, by which the accuracy of the alignment may be visually determined. In the particular construction shown, the device used is shown in Fig. 5. Each unit is provided with two such sighting devices. One is shown having a scale 42 provided with suitable graduations and a marker 43, this marker being provided with a right angled marking recess 44, this marker 43 being mounted on the scale board 42 so that it can be moved along the bar to any desired point, being held in adjusted position by a set screw 45.

This scale bar may be mounted on the unit in any suitable way. In the best construction, it will be pivoted so that when not in use it can be swung up out of the way. In the particular construction shown, therefore, the scale bar is pivoted at 46 to a bracket 47 secured to side framing of the unit at two convenient points, as at 48 and 49. In the use of these devices the bars are rocked from the dotted line position to the full line position shown in Fig. 5 and the markers 43 are suitably adjusted on the bars. If it is desired to align unit C with unit A, for instance, the scale bars on these units are swung into position and a line taken through the recesses 44 of the markers by means of a suitable instrument, such as a telescope, and the units are moved until the marking recesses 44 in all of the scale bars are in line, it being understood, of course, that the markers 43 of each scale bar are positioned at the same point on the scale.

My invention can also be applied to a press arrangement wherein a frame is provided in which the units are supported on a plurality of levels. One such arrangement is shown in Fig. 6. In this arrangement there is provided a second deck of printing units arranged above the deck shown in Fig. 1. These units are constructed and arranged like those in the lower deck and are provided with similar means for adjusting them. Two such units marked D, E are shown, the unit D being supported above the unit C, and the unit E above the unit B. Adjusting devices for these units similar to those already described are provided for these upper units, such devices being indicated by the numerals 50, 51. The upper units are supported in suitable framing marked 52, and the upper units may be driven from continuations of the vertical shafts which drive the lower units, as for instance unit D may be driven by shaft 18'.

Another application of the invention is shown in Fig. 7, when the printing units are arranged with their cylinders in line. In the construction shown in this figure the units are

arranged with their cylinders arranged in line or in an end to end relation. Two such units 55, 56 are shown; the unit 55 has its cylinders mounted in vertical frames 57, 58, and the unit 56 has its cylinders mounted in vertical frames 59, 60. The frames may be tied together by cross frames, as for instance a frame 61 ties together frames 59, 57. Slots 62 are formed in the tie frames to permit the adjusting movements of the units, and adjusting devices 63, 64 are provided for each unit.

A press unit is thus provided which may be assembled with its framing, its printing elements, either a printing couple or a perfecting mechanism, and its inking mechanism, moved as a whole, either with or without the cylinders, and quickly and readily associated with other press units without further assembly of its parts other than connecting up the driving mechanism therefor, or simply placing the cylinders in the journals. Thus, assembly of the unit at the press room is avoided and considerable saving of time by the user of the press effected in installing the units. It will be understood that the folder may be assembled as a unit and adjusted in a manner similar to that of the printing units, so that the folder can be aligned with the units with which it is used.

Owing to the weight of the cylinders it may be convenient to transport these separately. The bearings for the cylinders, however, will be in position in the framing and it will only be necessary for the user to put the cylinders in their bearings. The term pre-erected unit as employed in the specification and claims will be understood to include a unit that is complete or a unit complete except for the cylinders.

With the arrangement described, it will be seen that a simple and accurate means has been provided for aligning or truing up the press units in large multiple unit printing machines, and an improved unit arrangement which lends itself readily to quick installation.

While the mechanisms and arrangements shown and described are effective and practical, it will be understood that various changes may be made in these constructions and the invention, therefore, is not to be limited to the exact construction and arrangement shown and described.

What I claim is:

1. The combination of a base or support, a plurality of press units arranged in line on the support, and means arranged at each unit for adjusting the units in horizontal and vertical planes relatively to the support to align the unit with respect to any other unit so that the cylinders of the units will be in parallelism with each other.

2. The combination of a base or support, a plurality of press units arranged in line

on the support, and means arranged at each corner of a unit for effecting a horizontal and vertical adjusting movement of the unit relatively to the support to align the unit with respect to any other unit so that the cylinders of the units will be in parallelism with each other.

3. The combination of a base or support, a plurality of press units arranged in line on the support, and means secured to the support at the corners of the units for adjusting the unit relatively to the support to align the unit with respect to any other unit so that the cylinders of the units will be in parallelism with each other.

10 4. The combination of a base support, a plurality of press units having their cylinders arranged in parallel relation on the support, and means for effecting a swinging movement of a unit as a whole relatively to the support in a horizontal direction and a movement in a vertical direction to align the unit in parallel relation with respect to any other unit.

25 5. The combination of a base or support, a plurality of press units arranged in line on the support, means for adjusting a unit as a whole to align the unit vertically and horizontally in parallel relation with any other unit, and means for effecting a visual determination of the alignment.

30 6. The combination of a base or support, a plurality of press units arranged in line on the support, and wedges interposed between the units and the support for effecting an adjustment of the units.

35 7. The combination of a base or support, a plurality of press units arranged in line on the support, wedges interposed between the units and the support for effecting an adjustment of the units, and means for effecting a swinging movement of the unit to align it in parallel relation with respect to other units.

40 8. The combination of a base or support, a plurality of press units arranged in line on the support, wedge plates on the support at each corner of a unit, wedge blocks between the plates and the unit frames, means for manipulating the wedge blocks, and adjusting screws at each corner of the unit for effecting a swinging movement of the unit.

45 9. The combination of a base or support, a plurality of press units arranged in line on the support, wedge plates on the support at each corner of a unit, wedge blocks between the plates and the unit frames, means for manipulating the wedge blocks to effect a vertical movement of the unit, adjusting screws at each corner of the unit for effecting a swinging movement of the unit, and stops for holding the unit in adjusted position.

50 10. A pre-erected press unit including suitable framing and printing elements and ink-

ing mechanism assembled in the framing, and adjusting mechanism associated with the unit capacitated to adjust the unit vertically and horizontally, said unit being movable in its entirety and capable of ready association with other press units without further erecting.

55 11. A pre-erected press unit including suitable framing and printing and perfecting mechanism and inking mechanism therefor assembled in the framing, and adjusting mechanism associated with the unit capacitated to adjust the unit vertically and horizontally, said unit being movable in its entirety and capable of ready association with other press units without further erecting.

60 12. The combination of a base or support, a plurality of press units and a folder unit arranged in line on the support, and means for effecting an adjustment of the press units and the folder vertically relatively to the support so as to align a unit or the folder with any other unit.

65 13. The combination with a support of a plurality of press units arranged on the support, and means for aligning a unit in both a vertical and horizontal direction in parallel relation with any other unit.

70 14. A pre-erected press unit including a base and suitable framing secured to the base, printing elements and inking mechanism assembled in the framing, and adjusting mechanism associated with the unit capacitated to adjust the unit vertically and horizontally, said unit being movable in its entirety and capable of ready association with other press units without further erecting.

75 15. The combination of a base or support, a plurality of press units on the support, and means for adjusting the units vertically relatively to the support to bring the units into operating alignment with each other.

80 16. The combination of a base or support, a plurality of press units and a folder arranged in line on the support, and means for effecting an adjustment of the press units and the folder vertically and horizontally relating to the support so as to align a unit or a folder with any other unit.

85 17. The combination of a base or support, a plurality of press units on the support, and means for adjusting the units vertically and horizontally relatively to the support to bring the units into operating alignment with each other.

90 18. The combination of a base or support, a plurality of press units and a folder on the support, and means for adjusting the units vertically and horizontally relatively to the support to bring a unit or the folder into operating alignment with any other unit.

95 19. The combination of framing capacitated to receive and support press units provided with adjusting means, and having

means cooperating with the means on the units for effecting adjustment of the units vertically to bring the units into operating alignment.

5 20. The combination of framing capacituated to receive and support press units provided with adjusting means, and having means cooperating with the means on the units for effecting adjustment of the units vertically and horizontally to bring the units into operating alignment.

10 21. The combination of a base or support, a plurality of press units arranged in line on the support, means for adjusting a unit 15 as a whole to align the unit vertically and horizontally in parallel relation with any other unit, and precision devices secured to a unit for effecting a visual determination of the alignment.

20 22. The combination of a base or support, a plurality of press units on the support, and means for effecting a swinging movement of the units horizontally in any direction relatively to the support to bring the units into 25 horizontal alignment with each other.

25 23. A pre-erected press unit including suitable framing, and printing elements and inking mechanism assembled in the framing, and adjusting mechanism associated with the unit 30 and capacituated to effect a swinging movement of the unit horizontally in any direction, said unit being movable in its entirety and capable of ready association with the press units without further assembly.

35 In testimony whereof, I have hereunto set my hand.

HARRY G. KNOX.
